US00D570218S

(12) **United States Design Patent** (10) **Patent No.:** **US D570,218 S**
Crawford et al. (45) **Date of Patent:** **** Jun. 3, 2008**

(54) **UPPER PORTION OF A CONTAINER**

(75) Inventors: **John C. Crawford**, Mahopac, NY (US); **Roland Charriez**, Mohegan Lake, NY (US)

(73) Assignee: **Colgate-Palmolive Company**, New York, NY (US)

(**) Term: **14 Years**

(21) Appl. No.: **29/278,219**

(22) Filed: **Mar. 22, 2007**

(51) **LOC (8) Cl.** **09-01**

(52) **U.S. Cl.** **D9/516; D9/545**

(58) **Field of Classification Search** **D9/500, D9/502, 505, 516, 522, 530, 537, 539, 540, D9/542, 543, 544, 545, 549, 571, 574, 575, D9/687, 689, 691; 215/381-385, 396, 398**

See application file for complete search history.

(57) **CLAIM**

The ornamental design for an upper portion of a container, as shown and described.

DESCRIPTION

FIG. 1 is a perspective view of the upper portion of a container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of the lower portion of the container and the bottom of the container is for illustrative purposes only and forms no part of the claimed design.

1 Claim, 6 Drawing Sheets
